UNITED STATES PATENT OFFICE.

BENJAMIN S. BIRDSSL, OF BOWIE, LOUISIANA.

LIQUID-ELEVATING WHEEL.

SPECIFICATION forming part of Letters Patent No. 674,396, dated May 21, 1901.

Application filed February 7, 1901. Serial No. 46,350. (No model.)

To all whom it may concern:

Be it known that I, BENJAMIN S. BIRDSSL, a citizen of the United States of America, residing at Bowie, in the parish of Lafourche 5 and State of Louisiana, have invented certain new and useful Improvements in Liquid-Elevating Wheels, of which the following is a specification, reference being had therein to the accompanying drawings, in which—

10 Figure 1 is a side elevation of my improved wheel, partly in section; Fig. 2, a vertical transverse section thereof; and Figs. 3 and 4, vertical sectional views taken, respectively, on the lines 3 and 4 of Fig. 2.

15 This invention has reference to that class of water-elevators covered by my former patent, No. 609,655, dated August 23, 1898, in which is employed a wheel provided with a series of scoops adapted to successively dip 20 up the water as the wheel is rotated and empty it in a substantially continuous stream into a stationary tube supported concentrically within the wheel and extending laterally through an opening at one side of the wheel, 25 so as to discharge the elevated water into a spout at the side of the wheel.

The object of the present invention is to 30 improve and simplify the construction of the apparatus by providing for more efficiently supporting the wheel and doing away with the heavy driving-shaft formerly employed and the heavy shaft-bearings, which in my former machine obstructed the outlet ends of the discharge-tubes, as is more fully herein- 35 after set forth.

Referring to the drawings by letters, *a* designates the supporting-frame, and *b* the wheel, which latter is constructed, as formerly, of a pair of sides or disks *c*, connected by the curved elevating-scoops *d*. The wheel is mounted rigidly upon a rotatable horizontal shaft *e*, the opposite ends of which project outward through central openings in the respective sides of the wheel and are journaled in the hangers *f*, depending from the upper bars of hanger-frames *g*, which are bolted to the top of frame *a*. Extending out through the central opening in each side plate *c* is the discharge-tube *h*, which has openings *i* formed 45 in it at one side to receive the water from the inner ends of the scoops, as in my former patent. The tubes *h* are mounted station-

arily, their respective inner ends being supported close to the respective sides of the central hub *j* and their outer ends being respectively supported by metallic bands *k*, whose ends are spread outward from the tube and bolted rigidly to the vertical posts of the hanger-frame *g*.

Upon each side plate of the wheel is rigidly bolted a ring *l*, which surrounds the tube *h* and is provided with an outward-projecting annular flange *m*, which is supported by a pair of rollers *n*, journaled in a box *o*, mounted on the main frame. The rollers *n* are supported on either side of the vertical center of the wheel, and their shafts are parallel with the shaft *e*. It will be observed that with this manner of supporting the wheel most of the weight of the wheel and the water being 60 elevated will be borne by the flanges *m* and rollers *n*, thereby relieving the central shaft, of most of the strain and enabling it to be made very light in construction. Thus employing a light shaft, which performs in reality but little more than a centering device, 65 enables me to employ light hangers and to suspend them from a bar above the mouth of the discharge-tube, thereby avoiding the necessity of extending a supporting-bar across 70 the mouth of the discharge-tube and thereby obstructing it.

The discharge-spout *p* at each side is supported within the hanger-frame *g*, its inner end engaging under the flange *m*. Any suitable mechanism may be employed to rotate the wheel, though I prefer the devices shown, which consist of an internal gear or rack *q*, bolted to one of the side plates *c* and adapted to be driven by a pinion carried by the short 85 shaft *r*, journaled in suitable pedestals mounted rigidly on the frame.

I have described and shown my improvements applied to a double wheel adapted to discharge at both sides simultaneously; but 90 it is obvious that I may, as shown in my former patent, employ the improvements upon a single wheel—namely, a wheel constructed to discharge at but one side.

Having thus fully described my invention, 100 what I claim is—

In a water-elevating apparatus, the combination of a main frame, a wheel provided with water-elevating scoops and an opening in one

side, a shaft extending centrally through the wheel and a support for each end of this shaft, the one of supports which is adjacent the opening in the wheel side consisting of a 5 hanger-frame mounted on the main frame and carrying a hanger depending to a point coincident with the center of the wheel and engaging the adjacent end of the shaft, a stationary tube in the wheel and supported at 10 its inner end upon the shaft and extending out through said opening in the side of the wheel, means for supporting the outer end of

this tube, means for revolubly supporting the wheel at each side thereof and independently of the means employed for supporting the 15 shaft and tube, and means for rotating the wheel.

In testimony whereof I hereunto affix my signature, in the presence of two witnesses, this 4th day of February, 1901.

BENJAMIN S. BIRDSALL.
